UNITED STATES PATENT OFFICE

2,576,571

FILE BINDER

André Antoine Chauvin, Paris, France

Application April 2, 1947, Serial No. 739,012
In France October 8, 1941Section 1, Public Law 690, August 8, 1946
Patent expires October 8, 1961

6 Claims. (Cl. 24—66)

1

The present invention relates to a binding device which can be arranged in movable files of all kinds and which is characterised, among other advantages, by the fact that it can be adapted to a number of documents of very varied shapes, since it can ensure the maintenance of a single document of any dimension, as well as that of a hundred or even more, whilst having a thickness as reduced as possible, and that its very rapid manipulation, effected with one hand only, allows the other hand to be left free for introducing or removing documents, without the latter being deteriorated in any way whatever.

The invention is clearly illustrated in the accompanying drawing, in which:

Figure 1 is a perspective view showing the binding device applied to a file.

Figure 2 is a perspective view on an enlarged scale of the binding device in open position.

Figure 3 is a perspective view of the binding device on an enlarged scale in the act of being closed, and

Figure 4 is an enlarged perspective view of the binding device in a closed position.

Figs. 5, 6 and 7 are diagrams to allow the operation of the device to be understood when it is engaged with the documents to be kept in the file.

The movable file 1 is provided, as near as possible to its hinge 2, with the binder 3 and the latter allows the documents 4, 5, 6 of various dimensions to be sorted as will be clearly seen in Fig. 1.

The binder proper essentially comprises a flat base 7 serving to secure it on the file, for instance by means of two or three eyelets 8, and a partly bowed member 9, made of steel, having the shape of an H and pivotally mounted on said base.

Said base is turned upwardly according to a right angle at one of its edges to form an upstanding flange 10, bent at 11 and 12 at both its ends. The end 11 is folded to form a fork 13 in which is riveted the pin 14 on which can pivot, in a vertical plane, the main portion of the longer of the resilient bars 15 of the H-shaped member 9 according to the manipulations imparted to the latter by means of the handle portion 16, pivoted to the outer end of the bar 16 for horizontal swinging movement.

The other resilient bar 17 of member 9 and which is intended to firmly grip the documents is shorter than bar 15 and is bowed upwardly longitudinally so that when member 9 is lifted vertically on its pivot 14 (Fig. 2) the lower end 17 of said bar remains spaced away from the base 50

2

to a distance at least equal to the thickness of the documents which are to be placed in the file. The ends or wings 17¹ and 17² of bar 17 are preferably bent inwardly so as to form wide clamping surfaces.

The end 12 of flange 10 is cut out so as to form a yoke or lug 18 under which the handle 16 can resiliently engage, as seen in Fig. 3.

At its opposite edge the base 7 is preferably 10 slightly upset so as to form a projection 19 which accentuates the gripping of the document or documents in the closed jaw formed between said flange 19 and the bar 17. For the same purpose, said base can be provided with projections 20 obtained by upsetting, opposite the ends 17¹ and 17² of bar 17 (see Fig. 4).

The handle 16 can be cut out in the extension of bar 15 of the curved member 9, but it is preferable to pivotally mount it on the latter at 21 and to extend it by a small fork 22 freely engaged on a projection 23, obtained by upsetting, on the end of bar 15.

The manipulation of the device is very simple: the document or documents to be filed having been placed with their inner edges against the flange 10 of base 7, it suffices to lower the handle 16 and to engage it under the yoke or lug 18, said movement being facilitated by the pivotal joint 21, 22 of said handle on bar 15. The device then exerts, on the filed documents, a three-fold clamping, resilient and progressive effect, first by means of the curved bar 17 (Fig. 5) which transmits it to both clamping wings 17¹, 17², then by the cross member connecting bars 15 and 17 of the H-shaped member 9, which transfers, by flexion and torsion, on 15, the stress exerted on 17 (Fig. 6), finally by bar 15 also curved, on the base 7 secured to the back of the file (Fig. 7).

On the other hand, it suffices to press on the handle 16 to disengage it from the yoke or lug 18 and to laterally space it away, owing to the action of the pivotal joint 21, for the device to be lifted and cease to exert any pressure on the documents placed in the file.

It is to be understood that the embodiment described and illustrated is only given by way of example and that the profile and detail of all the members can be varied to infinity without departing thereby from the scope of the present invention. It is thus that the pivotal joint 21 of the handle might be done away with and transferred to the yoke which might pivot on the base 7, that the wings 17¹ and 17² might be double or extend only outwardly, etc.

I claim:

1. A binding device for movable files comprising a rectangular base plate, means to secure said plate to the back of a letter rack, an up-standing flange extending along the one larger side of said base plate and bent into a fork at one end thereof, an arched lug formed at the opposite end of said flange, an H-shaped member made up of resilient strips having its larger leg hinged at one end thereof in said fork at one end of said flange on said base plate, a latch pivoted to the other end of said larger leg as an extension of the same and projections formed at either end of the shorter leg of the H-shaped member extending at right angles thereto towards said larger leg.

2. A binding device according to claim 1 wherein the shorter leg of the H-shaped member is arcuated towards the base plate.

3. A binding device according to claim 1 wherein a rib is formed in the base plate at its longer edge opposite to the flanged edge thereof.

4. A binding according to claim 1 wherein the width of the H-shaped member is less than that of the base plate.

5. A binding device according to claim 1 wherein the longer leg of the H-shaped member is bent up at its free end.

6. Binding device for movable files comprising a rectangular base plate, means to secure the plate longitudinally to the back of a letter rack, an H-shaped member with resilient legs of un-

equal lengths, the longer of the legs having one end thereof hinged transversely to one side of said base plate for vertical swinging movement with respect thereto, a lug projecting laterally from said side of the base plate adapted to catch the free end of the longer leg of the H-shaped member and the shorter leg of the member being bowed upwardly medially of its ends and formed at either end with wings directed towards the longer leg and adapted to yieldingly bear upon the upper surface of the sheets being held.

ANDRÉ ANTOINE CHAUVIN.
